ILLUMINABLE SPRINKLER

Filed Jan. 14, 1932

UNITED STATES PATENT OFFICE

1,929,825

ILLUMINABLE SPRINKLER

William H. Requa, Portland, Oreg.

Application January 14, 1932. Serial No. 586,582

6 Claims. (Cl. 299—4)

The object of my invention is to provide an illuminable water spraying device, preferably in the form of a portable revolving lawn sprinkler.

In the warm evenings of the summer, lawn sprinkling is frequently done at night. The purpose of my invention is to utilize such spraying as a means for simultaneously producing a fountain-like spray, illuminated in changing colors; thus adding a charm to sitting out-of-doors in the summer evening.

A further object of my invention is to incorporate my invention in a portable revolving lawn sprinkler in such a way that the latter may be ordinarily used just as a mere lawn sprinkler.

15 A further object of my invention is to provide a device in which the operating parts are arranged and housed with regard to the aesthetic effect; also a device which may be made at reasonable cost; in other words, adding comparatively little to the cost of the ordinary revolving lawn sprinkler.

I attain my objects in an illuminable sprinkler comprising a tubular standard adapted to be connected with a water service pipe, the sprinkler 25 being of the revolving type, a horizontal vari-colored light screen carried by the sprinkler and means for projecting the rays of an illuminating element thru said vari-colored screen, thus producing constantly changing light effects and preferably I provide a sprayer above the sprinkler for projecting upwardly sprays to be illuminated by the light rays.

The further details of my invention and of its construction and use are hereinafter described 35 with reference to the accompanying drawing.

In the drawing:

Fig. 1 shows an elevation of a portable lawn sprinkler embodying my invention in its most complete form;

40 Fig. 2 shows a vertical central section of the operating parts of the lawn sprinkler shown in Fig. 1;

Fig. 3 shows a plan or top view of the sprinkler;

45 Fig. 4 shows a section approximately on the line 4—4 of Fig. 2, the parts shown in full; and

Fig. 5 shows a detail of the skeleton wall frame and housing which may be employed in the construction of my invention.

50 *a* is a portable standard on which is mounted a tubular standard *b* provided with a hose or pipe coupling *c* for connecting a hose as *d* with the standard *b*. The standard *b* is provided with a lower lateral branch *e* controlled by a valve *f*, and an upper branch *g* controlled by a valve *h*.

55 On the branch *e* is rotatably mounted a re-

volving sprinkler head *i* having radial arms *i'* terminating in nozzles *j*. The sprinkler head *i* carries a pedestal *k* on which to mount the figure as *l*. The upper branch *g* has a sprinkler ring *m* adapted to project a spray of water upward as indicated at *n* in Fig. 1. The sprinkler head *i* carries a vari-colored light screen *o* which may consist of segments of colored celluloid as indicated by *o'* in Fig. 3. The hollow standard *b* is provided with a bracket *p* which carries a housing *q* in which is mounted an electric lamp bulb *r*. This bulb is of the kind employed in automobile headlights and is connected by wires *s* with an electricity circuit, a transformer being included in the circuit *s* to permit the use of the desired small lamp bulb.

The housing *q* is provided with a parabolic reflector element *t*, and the housing *q* above the lamp bulb *r* is covered by a water shedding shield *u* so as to protect the interior of the housing *q* from the water dripping from the sprinkler *i* and spray ring *m*.

On the housing *q* is mounted a housing wall *v* which may consist of a skeleton wall frame *w* shown in Fig. 5 and sections of translucent colored celluloid *x*, *x'*. The revolving sprinkler is inclosed by a housing wall *y* supported on the screen *o*, thru which the nozzles *j* extend, as shown in Fig. 4.

In the operation of my illuminable sprinkler, if the same is to be used for lawn sprinkling purposes merely, the valve *f* alone is opened and the valve *h* is kept shut. When so arranged, my sprinkler will operate just as an ordinary lawn sprinkler of the revolving sprinkler type. While so operated, by turning on the electricity current of the lamp bulb *r*, rays of colored light will project upwardly thru the light screen *o*. This effect, however, is rendered much more beautiful and effective by partially closing the valve *f* and opening the valve *h*, in so doing, projecting a spray of water upwardly from the spray ring *m*; this spray changing in color with the rotation of the sprinkler *i* due to the travel of the color sections of the light screen *o* carried by the 95 sprinkler *i*.

In the drawing the arrows indicate the projection of the water from the heads of the revolving sprinkler *i* and the spray ring *m*.

The vari-colored light screen *o* is preferably 105 provided with an annular wall *z* constructed in the main of translucent colored material, in that way adding to the coloring effect of my lawn sprinkler when operating while illuminated.

I claim:

1. An illuminable sprinkler comprising, a tubular standard adapted to be connected with a service pipe, said standard having two lateral, valve-controlled branches, one above the other, 5 a revolving sprinkler carried by the lower branch, a horizontal vari-colored light screen carried by said sprinkler, a circular horizontal sprayer carried by the upper of said branches, an illuminating element carried by said standard including a reflector arranged to project the light rays 10 through said light screen and a housing including a transparent water shedding shield for said illuminating element.
2. An illuminable sprinkler comprising, a tubular standard adapted to be connected with a service pipe, said standard having two lateral, valve-controlled branches, one above the other, a 15 revolving sprinkler carried by the lower branch, a horizontal vari-colored light screen and a pedestal above the latter carried by said sprinkler, a circular horizontal sprayer carried by the upper of said branches, an illuminating element carried by said standard including a reflector arranged to project the light rays through said 20 light screen and a housing including a transparent water shedding shield for said illuminating element.
3. An illuminable sprinkler comprising, a tubular standard adapted to be connected with a service pipe, said standard having two lateral, valve-controlled branches, one above the other, a 25 revolving sprinkler carried by the lower branch, a horizontal vari-colored light screen carried by said sprinkler, a circular horizontal sprayer carried by the upper of said branches, an illuminating element below said vari-colored light screen including a reflector arranged to project the light rays upward through said light screen, and a 30 translucent housing for said lower branch and 40
4. An illuminable sprinkler comprising, a tubular standard adapted to be connected with a service pipe, said standard having two lateral, valve-controlled branches, one above the other, a revolving sprinkler carried by the lower branch, a horizontal vari-colored light screen carried by said sprinkler, a circular horizontal sprayer carried by the upper of said branches, a cylindrical translucent wall carried by said light screen, an illuminating element carried by said standard including a reflector arranged to project the light rays upward through said light screen and a housing including a transparent water shedding shield for said illuminating element. 80
5. In an illuminable sprinkler, a tubular standard adapted to be connected with a service pipe said standard having two lateral branches, one above the other, a revolving sprinkler carried by the lower branch, a horizontal vari-colored light screen carried by said sprinkler, a circular horizontal sprayer carried by the upper of said branches and an illuminating element below said vari-colored light screen including a reflector arranged to project the light rays upward. 85
6. In an illuminable sprinkler, a tubular standard adapted to be connected with a service pipe, a revolving sprinkler carried by said standard, a cylindrical section carried by said revolving 90 sprinkler, thru which the ends thereof project, a horizontal vari-colored light screen carried by said cylindrical section, a translucent cylindrical wall carried by said light screen, and an illuminating element carried by said standard including a reflector arranged to project the light ray thru said light screen. 95
